DESIGN FOR A GLASS CUTTER

William H. Shortell, Greenfield, Mass.

Application July 13, 1934, Serial No. 52,566

Term of patent 7 years

To whom it may concern:

Be it known that I, WILLIAM H. SHORTELL, a citizen of the United States of America, residing at Greenfield, in the county of Franklin and State of Massachusetts, have invented a new, original, and ornamental Design for a Glass Cutter, of which the following is a specification, reference being had to the accompanying drawing, forming a part thereof, in which:

Fig. 1 is a side view of a glass cutter embodying the invention;

Fig. 2 is a top view of the device shown in Fig. 1; and

Fig. 3 is a cross-section of the device shown in Fig. 1 taken along the line 3—3.

I claim:

The ornamental design for a glass cutter substantially as shown.

WILLIAM H. SHORTELL.
